UNITED STATES PATENT OFFICE.

JAY H. RATH, OF NEW YORK, N. Y., ASSIGNOR TO THE RATH LIGHT COMPANY, OF WILMINGTON, DELAWARE, A CORPORATION OF DELAWARE.

GAS-BURNER.

SPECIFICATION forming part of Letters Patent No. 739,558, dated September 22, 1903.

Application filed December 26, 1902. Serial No. 136,648. (No model.)

To all whom it may concern:

Be it known that I, JAY H. RATH, a citizen of the United States, and a resident of the city of New York, borough of Manhattan, 5 in the county and State of New York, have invented new and useful Improvements in Burners, of which the following is a full, clear, and exact description.

This invention relates to certain novel and 10 useful improvements in burners, and has particular application to the construction of a burner for use on incandescent gas-lamps.

In carrying out the present invention I have particularly in view the construction of 15 a burner which shall have the air and gas feeding ducts or passages so arranged and controlled that a mixture of any desired richness or proportions of gas and air may be readily obtained.

20 It is further my intention to so construct the gas check or feed controller of the gas-supply passage or duct that any quantity of gas from a minimum to a maximum volume may be admitted to the mixing-chamber of 25 the burner at will, thereby insuring that the desired proportions to obtain a light of certain candle-power or brilliancy may be positively had.

20 A further object of my invention is to form 30 a burner of a number of separable sections or parts, whereby the expense of constructing or manufacturing the burner is greatly reduced, certain of the metallic parts being readily made by stamping or the like. I also 35 contemplate forming the draft-tube of two sections or chambers, the upper section being relatively enlarged or widened, whereby the mixture ascending the tube and igniting above the screen formed in such enlarged 40 section may be burned with an increased candle-power, thereby adding to the lighting capacity of the lamp.

It is also the intention of the present invention to provide an improved burner which 45 shall embody the essential features of economy in the manufacture thereof and a consequent reduction of the price to the purchaser, while at the same time, owing to the relatively few parts composing the burner,

its simplicity will enable it to be installed 50 and managed by even inexperienced persons.

With these and other objects of a similar nature in view my invention consists in the peculiar construction, combination, and arrangement of parts, as is described in this 55 specification, delineated in the drawings, and set forth in the appended claims.

Reference is to be had to the accompanying drawings, forming a part of this specification, in which similar characters of reference indicate corresponding parts in all the figures.

Figure 1 is a side elevation of a burner embodying my improvement. Fig. 2 is a vertical longitudinal sectional view of the same. Fig. 3 is a perspective view of the air-regulating 65 collar. Fig. 4 is a top plan view of the main body portion of the gas check or regulator, and Fig. 5 is a similar view of the cap of the gas-check.

Referring now to the accompanying drawings in detail, 1 designates the base or cup-like portion of the burner, said base portion being preferably provided with a milled or serrated flange 2 and having a screw-threaded bore 3 extending centrally therethrough, 70 adapted to receive the end of a gas-pipe 4. The interior bottom surface of this base casting or portion is screw-threaded, as at 5, for receiving the circumferentially-threaded portion 6 of the gas-thimble 7. As will be seen, 80 this gas-thimble 7 is formed of a relatively wide base portion and a narrow tubular extension 8, a shoulder 9 being formed at the point of juncture between the narrow extension and the base portion referred to. The 85 top surface of the tubular extension of the thimble is provided with a number of perforations 10, as is clearly shown in Fig. 4, to permit the gas to flow from the pipe into the mixing-chamber.

90 For controlling the flow of gas through the bored or tubular portion of the thimble I have provided a peculiar form of check the construction of which is clearly shown in Figs. 2 and 5, this check comprising a cap 95 11, adapted to fit over the tubular extension of the thimble, such cap having a number of apertures formed in its top surface, which

are adapted to register with the apertures in the thimble when the cap is revolved thereon. The formation of these apertures is clearly shown in Fig. 5 and forms a very important feature of the invention, as the peculiar shape thereof enables the flow of gas into the mixing-chamber to be regulated from a minimum to a maximum volume with great positiveness. These apertures, which are shown at 12, are of approximately elongated segmental shape or pear-like conformation—that is to say, are formed with a widened portion gradually tapering to a point, as is clearly seen in the aforesaid Fig. 5. When the cap is placed upon the extension of the thimble, it may be turned or revolved, so that the pear-like apertures may fit over the orifices in the thimble, so that the full flow of gas passes through the enlarged or widened portion of the apertures in the cap. When it is desired to dispense with the maximum volume of gas passing through the thimble, the latter may be turned so that the minimum volume may be obtained by causing the points of the pear-like apertures to be in alinement with the aforesaid orifices of the tubular extension. For the purpose of assisting in revolving the cap upon the extension of the thimble the annular flange thereof, as at 13, may be milled or serrated.

The exterior of the base portion 1 is provided with a circumferentially-extending shoulder 14 and an upwardly-extending screw-threaded flange 15, said flange being adapted to be engaged by a correspondingly-threaded base portion of the casing 16 of the mixing-chamber. This casing is provided with a number of elongated orifices 17, which are adapted to aline with corresponding orifices 18, formed in the collar 19, which revolvably surrounds said casing. As will be evident, the air adapted to commingle with the gas to form the lighting mixture passes through the apertures in the walls of the casing into the mixing-chamber and may be regulated by turning the said collar 19, the solid portion 20 formed between the orifices in the collar being adapted to partially or entirely cover the elongated slots in the casing, thereby regulating the amount of air admitted to the chamber. This mixing-chamber I have designated as a whole by 21, and the upper portion of the casing thereof is provided with a reduced extended portion 22, adapted to receive the lower end of the draft-tube, which tube is formed of two portions 23 and 24. The lower portion 23 is approximately truly cylindrical or straight, while the upper portion thereof is flared outwardly or widens, as at 25, until the top thereof, as at 26, is of greater diameter in cross-section than any other part of the aforesaid draft-tube. This top portion 26 is surmounted by the movable cap 27, carrying the usual gauze 28. Near

the point of juncture with the lower portion 65 of the draft-tube the said enlarged upper section is circumferentially threaded, as at 29, for supporting the chimney-holder 30, which may be of any ordinary or preferred construction and is preferably provided with a 70 socket 31 for retaining the rod 32 of an incandescent mantle. (Not shown.)

The construction and operation of my improved burner will be readily apparent from the above description when read in connection with the accompanying drawings. The numerous advantages incident thereto will also be appreciated, and while I have shown and herein described one particular embodiment of my invention it will be evident and is to be understood that I do not limit myself to the precise details of the construction shown herein, as there may be modifications and variations in certain respects without departing from the principle or scope of the invention or sacrificing any of the essential features thereof.

Having thus described my invention, I claim as new and desire to secure by Letters Patent—

1. A burner comprising a mixing-chamber, means for regulating the admission of air thereto, an orificed tube for conducting gas to said chamber and a gas-check surmounting said tube, the said check having apertures which are of varying cross-diameter formed therein and elongated in a circumferential direction, the check being movable to bring the apertures thereof into alinement with the orifices in the tube, substantially as set forth.

2. The combination with a gas-burner, of means for regulating the admission of gas thereto, such means comprising an orificed thimble in the chamber, and a revoluble check upon said thimble, said check having concentrically-arranged elongated segmental apertures of varying cross-diameter therein said apertures being extended longitudinally in a circumferential direction and adapted to register with the apertures in the thimble, substantially as set forth.

3. The combination with a gas-burner, of means for regulating the admission of gas thereto, such means comprising an orificed thimble in the chamber, and a revoluble check upon said thimble, said check having apertures of varying cross-diameter elongated in the direction of rotation of the check, such apertures being of approximately circular contour at their widest points gradually tapering to an apex at their point of narrowest diameter, substantially as set forth.

4. In a burner, the combination of a draft-tube formed of sections of varying cross-diameter, means for regulating the amount of air admitted to the burner, an orificed tube for conducting gas to said burner, and a gas-

check having concentrically-arranged pear-shaped apertures of varying cross-diameter surmounting said tube and elongated in a circumferential direction, the check being
5 movable to bring the apertures thereof into alignment with the orifices in the tube, substantially as set forth.

In testimony whereof I have signed my name to this specification in the presence of two subscribing witnesses.

JAY H. RATH.
